REFRIGERANT COMPRESSOR STRUCTURE

John R. Replogle, Detroit, Mich., assignor, by
mesne assignments, to Copeland Refrigeration
Corporation, Mount Clemens, Mich., a corpora-
tion of Michigan

Application June 6, 1932, Serial No. 615,513

5 Claims. (Cl. 230—230)

This invention relates to mechanisms for compressing fluids and has particular relation to the construction of the valves and other parts of such compressing mechanisms.

5 An object of the invention is to provide a simplified and efficient mechanism for compressing fluid such as the working fluid in refrigerating systems and in which the working parts are capable of operation at relatively high speeds to perform the functions thereof in response to extremely rapid variations in the pressure of the working fluids operated upon.

Another object of the invention is to provide a refrigerant compressor having working parts capable of operation with the least possible amount of noise in order that the mechanism will not be objectionable to the occupants of a home in which it is employed.

Another object of the invention is to provide a compressing mechanism having relatively light and inexpensive working parts such that their operation at relatively high speed will not create objectionable noises and vibrations which might otherwise result therefrom.

Another object of the invention is to provide compressor suction and discharge valves which will operate quietly and efficiently at high speeds and which are simple, light and durable enough to give efficient and reliable service in small, directly driven refrigerant compressors especially adapted for small refrigerating system purposes.

Another object of the invention is to provide refrigerant compressor valves which require little clearance space for their operation.

35 Another object of the invention is to improve the operational characteristics of ordinary disc valves when employed as suction and discharge valves in small refrigerant compressors.

Another object of the invention is to reduce the resistance to the flow of fluid both inwardly and outwardly of a compressor cylinder of which operation and high speed is required.

The embodiment of the invention disclosed herein for the purpose of illustration comprises a cylinder having an end portion thereof closed by a plate through which fluid compressed in the cylinder is discharged into a cylinder head enclosing the space thereabove. A piston reciprocating in the aforesaid cylinder is provided with a plurality of ports through the head thereof which are adapted to supply refrigerant vapor to be compressed within the cylinder when the piston moves downwardly therein. In order to prevent the escape of refrigerant through said ports on the upstroke of the piston the ports are closed

by an annular disc valve secured at its center upon a movable pin, the movement of which is limited by a nut engaging a portion of the piston head. The valve plate, which also is provided with openings permitting the discharge of refrigerant from the cylinder upon the upstroke of the piston, is provided with a similar annular disc valve for automatically closing the port when the piston reaches the outer limit in its path of travel. This valve is held resiliently in position 10 by a suitable spring within a cage secured upon the valve plate in any suitable manner. All portions of the aforesaid valve structure are constructed of extremely light and durable parts capable of operating without attention for long 15 periods at comparatively high speeds.

In the drawing:

Figure 1 illustrates a fragmentary vertical sectional view through a refrigerant compressor constructed according to the principles of the invention;

Fig. 2 is a horizontal sectional view through the compressor taken substantially on line 2—2 of Fig. 1;

Fig. 3 is a fragmentary horizontal sectional view taken on line 3—3 of Fig. 1;

Fig. 4 is another fragmentary horizontal sectional view taken substantially upon line 4—4 of Fig. 1, and

Fig. 5 is a fragmentary vertical sectional view 30 of a slightly different form of compressor structure illustrating the principles of the invention.

Referring particularly to the drawing there is employed a compressor 10 which may be of any type desired although in the present instance a 35 reciprocating type of compressor is disclosed for the purpose of illustration. Such compressor comprises principally a cylinder 11 having there-in a piston 12 provided with a piston pin 13 to which a connecting rod 14 is secured for driving 40 the compressor piston in a reciprocating path of movement from a crankshaft or other similar device (not shown). The crankshaft preferably is connected directly to a relatively small high speed motor for driving the piston at a corresponding rate to expel from the cylinder a large amount of gas in proportion to the size thereof. The upper end of the cylinder 11 is covered by a valve plate 16 which in turn has secured there-on by means of bolts 17 a cylinder head 18 adapt-ed to receive and to collect the high pressure gas 50 delivered by the compressor.

The head 19 of the piston is provided with a centrally disposed opening in which is secured a compressor suction valve 21 which is adapted 55

to open in response to the downward movement of the piston to admit gas to the region thereabove and to close upon the upward movement thereof to prevent the escape therethrough of the gas so admitted. The exterior surface of the piston head 19 is so recessed as to receive therebeneath an annular disc 22, the outer edge of which is adapted to rest upon an annular seat 23 formed in the recessed upper or head portion 10 of the piston and engaging the lower surface of the disc.

The annular space 24 formed around the outside of the seat 23 communicates with the region above the piston 12 and below the valve plate 16 through a small clearance space formed between the piston and the outer edge of the disc 22. The annular space 26 inside the seat 23 communicates through a plurality of openings 27 with the inside of the piston 12 and the crankcase of the compressor which in turn is connected with an evaporating unit of a refrigerating system (not shown).

The inner periphery of the disc 22 rests upon the upper extremity of an annular boss 28 surrounding the opening in which the valve 21 is slidably disposed. The disc 22 is secured for operation within the piston head 19 between a relatively flat head 29 of a bolt 32 engaging the upper surface thereof and the upper extremity of a sleeve 31 slidably disposed within the boss 28 and secured upon an intermediate portion of the bolt by a nut 33 engaging the lower extremity thereof. The nut 33, which is threaded upon the bolt 32, is permanently secured in position to prevent the loosening of the parts of the valve 21 by having the lower extremity of the bolt 32 projecting therebeyond enlarged or upset as is indicated at 34.

In order to provide for an appreciable movement of the valve 21 with respect to the piston 12 the sleeve 31 is made somewhat longer than the length of the boss 28 to provide on the upstroke of the piston a slight space between the boss and the nut 33. Thus when the piston reaches the upper limit of its stroke the inertia of the parts of the valve 21 tends to carry the valve onwardly until the nut 33 abuts the lower extremity of the boss 28. This movement of the valve bodily raises the disc 22 off the seat 23 and on the downstroke of the piston the low pressure gas within the compressor crank case flows through the ports 27, the annular space 26, between the annular seat 23 and the disc 22, and into the unoccupied space above the piston. When the piston reaches its downward limit of travel the cylinder is closed also by the inertia of the parts of the valve 21 which tends to seat the disc 22 upon the seat 23 at the beginning of the movement of the piston in the opposite direction. The valve thus seated prevents a return flow of the gas admitted to the cylinder from the crankcase whereupon the gas is compressed within the cylinder upon the movement of the piston in the opposite direction.

At the upper limit of travel of the piston 12 the head surface thereof and the upper surface of the disc 22 extends within close proximity to the lower surface of the valve plate 16. In order to prevent the bolt head 29 from striking against the valve plate the latter is provided with an opening 36 just large enough to admit the head without creating an excessive amount of clearance space within the cylinder.

Just above the outer extremity of the disc 22 are located a plurality of openings 37 formed in

the valve plate 16 for the purpose of permitting the discharge of compressed gas from within the cylinder to the space within the head 18. These openings or ports communicate with an annular opening 38 formed in the upper surface of the valve plate 16 between a pair of annular seats 39 and 41 terminating at their upper extremities in approximately the plane of the upper surface of the valve plate 16. At the inner extremity of an annular opening 42 formed inside the annular seat 41 is a boss 43 around which is seated a flange 44 formed at the inner periphery of a relatively flat valve securing cage 46 of a compressor discharge valve 47. The outer periphery of the cage is formed to provide an annular rim 48 which terminates in an outwardly projecting flange 49 by which the cage is secured in position beneath the head 18 in an annular recess 51 formed outside the annular seat 39.

Mounted on the outer surface of the flange 44 and beneath the cage 46 is an annular disc 52 the lower surface of which rests upon the upper extremities of the annular seating rings 39 and 41. The disc is resiliently held in position upon such rings by a spring 53 formed with an inner annular part 53 engaging the outer surface of the flange 44 and resting upon the upper surface of the disc 52. The outer periphery of such annular part terminates in a plurality of radially extending arcuate arms 54, the outer ends of which are adapted resiliently to engage the lower surface of the cage 46 in the vicinity of the rim 48 to hold the annular part 53 against the upper surface of the disc 52. The cage, 46, at the outer edge of the rim 48, is provided with a plurality of slots or openings 56 providing communication between the interior of the head 18 and the space below the cage.

When the gas is compressed within the cylinder upon the upstroke of the piston 12, as has been described hereinbefore, the disc 52 remains seated on the annular seats 39 and 49 until the gas within the cylinder reaches a pressure great enough to overcome the resilient force exerted by the spring 51 and the pressure of the gas within the head 18. Any further increase in the pressure within the cylinder then lifts the disc 52 off the seats 39 and 41 thus permitting compressed gas to flow from the cylinder through the ports 37 and the annular port 38, between the annular seat 39 and the lower surface of the disc 52, and outwardly from beneath the cage 46 through the slots 56.

When the piston reaches its upper limit of travel and all the excess gas is expelled from the cylinder 11 the spring 51 then moves the disc 52 again into seating position upon the annular seats 39 and 41 to close the cylinder against the return flow of gas from the head 18 during the downward movement of the piston thereafter occurring.

The passages through both the piston head 19 and the valve plate 16 are large enough to permit the rapid flow of gas therethrough without creating excessive friction in so doing. Also the valve seats 23 and 39 in the piston head 19 and valve plate 16 respectively, are relatively large in diameter to provide a relatively large space between the seats and the discs 22 and 52 respectively, without excessive movement of the latter. The discs 22 and 52 preferably are made of spring material to insure quietness of operation of the valves although the discs are constructed to open in response to the operation of the compressor without reliance upon the flexible quality thereof.

In the structure disclosed by Fig. 5 the valve plate 16 has the upper surface thereof cut out in such manner as to receive therebeneath the greater portion of a relatively flat valve cage 61 which is secured at its edges in such recess beneath the head 18. A central portion of the cage is provided with an opening 62 into which projects a boss 63 formed in the valve plate in a central portion of the aforesaid recess therein. Beneath the cage 61, there is provided sufficient space for the operation of a spring 64 and a disc 66, the latter of which rests upon a pair of annular seats 67 and 68 formed in the valve plate 16 around the boss 63. The construction of the spring 64 and disc 66 is very much like the construction of the spring and disc respectively employed in the structure previously described except that the disc 66 is relatively small in diameter compared with the spring 64 and consequently the force of the spring is applied to the disc in a region nearer the outer periphery thereof.

The suction valve 21 employed in this structure consists of a disc 69 disposed beneath the upper surface of the piston 12 and welded or otherwise secured to a tubular retaining member 71 disposed slidably in an opening formed in the head of the piston 12. The outer edge of the disc 67 is supported upon an annular seat 72 formed in the head surface of the piston 12 and with the space inside of which the interior of the piston communicates through arcuate slots 73 formed in that portion of the retaining member 71 adjacent which the disc 69 is secured. These slots not only provide ports for the passage of gas through the piston 12 but serve to prevent distortion of the disc by permitting expansion and contraction of the elements of the valve independently of one another. The lower extremity 40 of the tubular retaining member 71 is provided with an outwardly projecting flange 74 which is spaced slightly below the lower extremity of the boss 28 formed in the piston head 19 and around the opening in which the tubular member 71 is slidably disposed.

In the operation of the structure the gas within the compressor flows through the ports 73 and over the annular seat 72 on the downward movement of the piston 12 when the inertia of the 50 valve causes the flange 74 to engage the lower extremity of the boss 28 after the reversal in movement of the piston. Thereafter upon the upstroke of the piston the disc 69 is seated upon the annular seat 72. When the gas contained within the cylinder is compressed sufficiently the disc 66 moves off the seats 67 and 68 to permit the gas to escape to the interior of the head 18.

While the structure as herein disclosed constitutes a preferred form and application of the invention, it is to be understood that numerous modified and equivalent structures are within the scope of the invention as defined by the appended claims.

I claim:

1. The combination with a cylinder having a valve plate and a head secured thereon, said valve

plate having a projection extending upwardly from a central portion thereof, of a cage disposed within said head upon said valve plate and having an opening formed therein for receiving the aforesaid plate projection, said cage also having an outwardly projecting flange secured in a recess between said head and valve plate and a valve secured between said valve plate and cage for controlling the flow of fluid through the former.

2. The combination with a compressor having a valve plate and a head secured thereon, said valve plate having a pair of annular seats formed beneath the upper surface thereof, of an annular valve supported by said seats for preventing the flow of fluid inwardly of said compressor through openings formed in said valve plate, an arcuate spring disposed upon the upper surface of said valve for resiliently retaining the latter in position upon said seats, a cage for retaining said valve and spring in position, said cage having a laterally projecting annular flange formed at the center thereof and projecting within a recess formed in said valve plate, and a radial flange at the outer periphery thereof extending within a recess between said valve plate and head and confined therein for securing the elements of the aforesaid valve structure in operative position.

3. The combination with a compressor having a valve plate and a head secured thereon, said valve plate having a recess formed in the surface thereof adjacent said head and extending beneath the inner edges thereof, of a substantially flat valve cage secured upon said valve plate with the edges thereof confined beneath said head, the major portion of said valve cage being disposed below the upper surface of said valve plate, and a compressor discharge valve confined beneath said valve plate for controlling the flow of working fluid operated upon by said compressor.

4. In a compressor structure the combination of a cylinder, a valve plate, and a head secured thereon, said valve plate having a recess formed therein in the surface thereof adjacent said head, a valve cage confined within said recess between said head and valve plate, the greater portion of the surface of said cage being inside the exterior limits of said valve plate, a projection formed centrally of said valve plate and extending through an opening formed in said cage, an annular disc valve surrounding said projection and confined between said cage and valve plate, and a spring between said disc valve and valve cage for resiliently retaining said valve in position.

5. The combination with a cylinder, of a substantially flat valve plate and a head secured thereon, the upper surface of said plate being annularly recessed whereby to provide an upwardly extending projection centrally thereof, a pair of spaced and concentric valve seats on said plate concentric with said projection, an annular valve engageable with said seats, a cage for said valve overlying said plate, and a downwardly directed tubular sleeve on said cage encircling said projection and being encircled by said valve.
